CIGAR ROLLING MECHANISM

James P. Durning, St. Albans, N. Y., assignor to
 International Cigar Machinery Company, a
 corporation of New Jersey

Application March 13, 1940, Serial No. 323,673

6 Claims. (Cl. 131—36)

This invention relates to cigar rolling mechanisms for applying a wrapper to a shaped cigar bunch, more particularly to improvements in the mechanism for operating the tuck needle which strips the tuck end of the wrapper from the wrapper carrier and holds it against the bunch during the first turn or two of the latter while it is being wrapped on the same.

An object of the invention is to provide a safety mechanism to prevent the accidental breakage of the tuck needle or its support when cigar machines of the type shown in the co-pending application of H. H. Wheeler, S. N. 208,972, filed May 20, 1938, on which Patent No. 2,235,857 was issued on March 25, 1941, are cranked backwards for examination or adjustment of the parts.

In the prior operation of the tuck needle, the same slides forward from its rest position after the spring-pressed latch which holds it down is automatically released during the rearward movement and contact of the needle therewith, and tilts up and enters a slot in the tuck end of the carrier whereon the wrapper is suctionally held. The needle then presses the tuck end of the latter down upon the bunch in the wrapper-applying device and holds it against the bunch during the first stages of the wrapper rolling operation. When this tilting latch is accidentally released manually, or otherwise as by cranking the machine backwards, the tuck needle will project upwardly into the path of the transversely moving carrier head, and if the needle is not held down manually, the head will strike the same and may break it.

The present invention eliminates this condition. Instead of the latch heretofore used, a cam may be provided to actuate a spring-tensioned double lever carrying a cam piece which supports the rear end of the needle and thus holds its forward end down, except for that brief period of the cycle when the needle is actually required to perform its stripping action. At this time the carrier head is at rest directly above the cigar bunch in the rolling device and has a slot for the entrance of the needle in registering position with the forward and upward path of the latter. In this manner, the needle is positively locked in its down-position during all portions of the cycle in which harm can come to it from the moving wrapper transfer.

In the accompanying drawing which forms a part of this specification and in which like characters of reference indicate the same or like parts;

Fig. 1 is a side elevation of the rear portion of a cigar rolling device, showing the improved mechanism for operating the tuck needle;

Fig. 2 is an end view of the cigar rolling device, seen from line 2—2 of Fig. 1; and

Fig. 3 is a sectional side elevation on line 3—3 of Fig. 2, showing the cam for operating the tuck needle.

Referring to Figs. 1 and 2, the tuck needle 10 is carried by a holder 11 connected by a link 12 to an arm 13 affixed to a shaft 14 of a wrapper rolling unit 15 which may have any suitable construction such as disclosed in my co-pending application, S. N. 107,792, filed October 27, 1936.

In this unit the needle 10 is guided by a bushing 16 into the space between the rollers 17 and 18 which support and rotate the cigar bunch C while a wrapper W is rolled onto the same. The top rollers 17 are intermittently moved apart to admit the bunch C delivered onto the bottom rollers 18 by a suitable transfer from the bunch shaper. After reclosing of the rollers 17, the needle 10, by the mechanism hereinafter described, is permitted to tilt up and move forward into position 10' shown in dotted lines, thereby entering into a slot 19 in the head 20 of a carrier which has brought a wrapper W from a die on which it has been cut, the carrier head 20 at this moment being in the proper position over the rollers 17. In passing through slot 19, the needle 10 passes over the tuck end of the wrapper W which is held to the head 20 by suction. While the carrier 20 dwells in its delivery position, the needle 10 then moves down, carrying the wrapper end, from which the suction has in the meantime been released, onto the tuck end of the cigar bunch C and holding it thereon for one or more turns of the rollers 17 and 18 until it is secured in position by the lap of the second turn, whereupon the needle moves back into starting position.

The attachment of the needle 10 to the holder 11, and that of the latter to the link 12 is disclosed in the co-pending application of S. Clausen, S. N. 267,232, filed April 11, 1939, on which Patent No. 2,281,095 was issued on April 28, 1942. The axial motion and the wrapper stripping action of the needle 10 is effected by a cam lever 21 on shaft 14, this cam lever having a roller 22 held by a torsion spring 23 against the cam face of a barrel cam 24 mounted on the cam shaft 25 of the rolling unit, the spring 23 at one end being anchored to the frame of unit 15 and at the other to a collar 26 on shaft 14. As the raised portion 27 of cam 24 enters under roller 22, the

lever 21 is moved into position 21', thereby turning arm 13 through an arc shown by arrow 28, into the position which corresponds with the forward position 11' of holder 11.

The needle 10 is guided laterally by a slotted plate 29 adjustably attached to a bracket 30 on the frame of unit 15 and is supported in its horizontal position by a cam piece 31 affixed to a cam lever 32 having a roller 33 held against the circumference of a raised circular cam track 34 on the rear face of cam 24 by a torsion spring 35, but the cam piece 31 is rapidly withdrawn to position 31' at the beginning of the forward motion of the needle toward position 11' to permit the needle to tilt upwardly. For this purpose the track 34 has a depression 36 at a predetermined position with respect to the raised portion of the cam 27 on the forward face. The lever 32 is pivoted in a lug of bracket 30 by a pin 37 on the end of which is mounted a collar 38 in which is fastened one end of spring 35 whose other end is anchored in bracket 30. The spring 35 is enclosed by a tubular cover 39 attached to collar 38. The hub of cam 24 is formed with integral jaws 40 by which it is clamped to a bushing 41 held tight on cam shaft 25 by a plate 42 forced against the bushing by a screw 43 in the end of the shaft.

Just before the lever 13 is moved forward by the cam surface 27, the cam depression 36 engages the roller 33. Thus the roller 33 is swung into position 33' by the spring 35, thereby moving the cam piece 31 from the position wherein it supports the rear end of the needle 10, into position 31'. Thus, when the support at the rear end of needle 10 is removed during the forward movement of arm 13, the forward end of the needle tilts upwardly until the rear end comes to rest on a cross plate 44 adjustably attached to guide plate 29. Shortly afterward, in this tilted position, the needle during the continued forward movement of arm 13, passes into the slot 19 of wrapper carrier head 20, so that before re-engagement of cam roller 33 with cam track 34, the down-stroke of needle 10 due to the engagement of holder 11 with bushing 16, will have stripped the tuck end of wrapper W from the carrier head and deposited it on the cigar bunch C. The needle assumes a horizontal position when it deposits the tuck end of the wrapper upon the bunch and stays horizontal while cam piece 31 moves back under the rear end of the needle, and the wrapper is held on the bunch during the passage of the raised cam portion 27 under cam roller 22, and then the arm 13 moves back into its initial position while the needle 10 is held horizontally by the cam piece 31. The cam piece 31 remains in position under the needle 10 as long as the roller 33 stays on the circular portion of track 34, hence the needle can enter into the path of carrier 20 only during the passage of the depression 36 under the roller 33, but during this brief period no harm can come to the needle as the carrier then is stationary.

What is claimed is:

1. In a cigar rolling device having a wrapper carrier movable into wrapper applying position and having a slot at its tuck end arranged to admit a tuck needle when the wrapper carrier moves into wrapper-applying position, the combination with a tuck needle, of means for advancing said needle into a forward position and then returning the needle to initial position, said means including a device normally supporting said needle in an upwardly tilted position to,

enter the slot in the wrapper carrier when at its forward position, a member for swinging said needle downwardly from said slot to pull down the tuck end of a wrapper from the wrapper carrier, mechanism for maintaining said needle in a position with its tip below the path of said carrier during the rearward movement of the needle, said mechanism including a cam lever supporting the rear end of said needle to maintain it in a substantially horizontal position, and a cam controlling said lever to permit said needle to tilt upwardly into position to enter said slot.

2. In a cigar rolling device having a wrapper carrier movable into and away from wrapper applying position and having a slot at its tuck end arranged to admit a tuck needle when the carrier is at wrapper-applying position, the combination with a member movable toward and from the wrapper-applying position of the carrier, a tuck needle, means connecting said needle to said member for movement with the latter, means for maintaining said needle in an upwardly inclined position whereby the needle will be moved into said slot during the movement of said member toward said carrier, means for swinging said needle down from said slot to strip the tuck end of a wrapper from the carrier, a cam lever, a support connected to said cam lever, and a cam for operating said lever to move said support into position to engage said needle and maintain it in a position with its tip below the path of said carrier during the movement of said member away from the wrapper-applying position of the carrier.

3. In a cigar rolling device having a wrapper-carrier movable into wrapper-applying position and provided with a slot in its tuck end arranged to admit a tuck needle when the carrier is at wrapper-applying position, the combination with a member movable toward and away from the wrapper-applying position of the carrier, a tuck needle, mean connecting said needle to said member for movement with the latter, means for maintaining said needle in position to enter said slot as said member approaches the wrapper-applying position of the carrier, means actuating said needle to strip the tuck end of a wrapper from the carrier, and mechanism moving in timed relation to the movement of said member into position to engage and maintain said needle in a position with its tip out of the path of the carrier while said member moves away from the wrapper-applying position of the carrier.

4. In a cigar rolling device having a wrapper-carrier movable into wrapper-applying position and provided with a slot in its tuck end arranged to admit a tuck needle when the carrier is at wrapper-applying position, the combination with a member movable toward and away from the wrapper-applying position of the carrier, a tuck needle movably connected to said member, means controlling the movement of said needle to cause it to enter said slot while the wrapper-carrier is at wrapper-applying position and strip the tuck end of the wrapper from the carrier, a device adapted to be moved into engagement with said needle and maintain it in a position with its tip out of the path of the carrier during the wrapper-applying position of the carrier, and mechanism operating in timed relationship to the movement of said member to move said device into engagement with said needle to maintain it in a position with its tip out of the path of the carrier during the movement of said mem-

ber away from the wrapper-applying position of the carrier.

5. In a cigar rolling device having a wrapper carrier movable into wrapper-applying position and provided with a slot in its tuck end arranged to admit a tuck needle when the carrier is at wrapper-applying position, the combination with a cam lever, of a member connected to said lever for movement with the latter, said needle being movably connected to the member connected to said lever, means for maintaining said needle in an upwardly inclined position in which it will enter said slot as it approaches the wrapper-applying position of the carrier, a stationary member arranged to engage and swing down the needle to strip the tuck end of the wrapper from the carrier, a rotating cam shaft, a pair of cams fastened to said shaft, one of said cams operating said lever to move it toward the wrapper-applying position of the carrier, and a member operated by the other of said cams and adapted to maintain the needle in a horizontal position during the rearward movement of said lever.

6. In a cigar rolling device having a wrapper carrier movable into wrapper-applying position and provided with a slot in its tuck end arranged to admit a tuck needle when the carrier is at wrapper-applying position, the combination with a cam lever, of a member connected to said lever for movement with the latter, said needle being movably connected to the member connected to said lever, means for maintaining said needle in an upwardly inclined position in which it will enter said slot as it approaches the wrapper-applying position of the carrier, a stationary member arranged to engage and swing down the needle to strip the tuck end of the wrapper from the carrier, a rotating cam shaft, a pair of cams fastened to said shaft, one of said cams operating said lever to move it toward the wrapper-applying position of the carrier, and a member operated by the other of said cams and adapted to maintain the needle in a horizontal position during the rearward movement of said lever.
